UNITED STATES PATENT OFFICE.

CHARLES H. SMOOT, OF MAPLEWOOD, NEW JERSEY.

CENTRIFUGAL GOVERNOR.

Application filed October 22, 1926. Serial No. 143,416.

This invention relates to centrifugal governors of the class characterized by a rotatable liquid container in which a stationary disk is caused to move axially with a force proportionate to the speed of the container by virtue of vanes on both the container and the disk. Such a governor is shown in my prior Patent No. 1,530,740 dated March 24, 1925.

It has been found in practice that there is a tendency in governors of this kind for the liquid to creep up along the surfaces of the apparatus above the liquid until it reaches a point where the centrifugal force of the rotating parts causes such leakage liquid to be thrown off with the result that the level of the liquid is soon lowered to a point where the efficiency of the apparatus as a governor is impaired. It has also been found in practice that a small accumulation of air sometimes occurs under the disk due to leakage or turbulence and this air being an elastic medium interferes materially with the efficiency of the device as a governor, for the reason that the governor is designed to work only with inelastic fluids.

It is the object of the present invention to overcome these defects. To prevent the liquid from creeping up to a point where it can be thrown off, I have found that if the central shaft is made to fit as a journal, the riser on the rotatable member, the said journal fit terminating some distance below the top of the riser, that this leakage can be prevented and that if the shaft carrying the stationary disk has an air vent extending from the lower surface of the disk up through the shaft with outlets through the shaft of the journal bearing at a point above the liquid line with a further air vent extending from this first air vent up through the vertical rod that connects the shaft with the governor actuated mechanism and thence through said rod, the air will be bled from the space below the disk and discharged into the atmosphere while any liquid accompanying the air or creeping up along the inside of the air vent will be discharged into the journal bearing.

The invention will be better understood by a detailed description in connection with the accompanying drawing, which represents a speed governor in axial section.

1 represents a shaft geared to the mecha-

nism whose speed is to be regulated. Secured to this shaft and rotatable with it is a casing 2 adapted to contain liquid. A hollow riser or column 3 extends from the upper part of this casing. In the casing is a non-rotatable disk 4 having a hollow riser or shaft 5 fitting with a journal fit in the column 3. The shaft 5 has a connecting rod 6 extending vertically to a point where it is connected by a pivot 7 with a lever 8 that may be the controlling lever of a throttle valve or other speed varying means. The rod 6 is coupled to the shaft 5 by a universal ball and socket joint 6' to allow for flexure at the joint in case of any misalignment of the center line of the shaft 5 with the pivot 7. Pins 6" in the shaft and connecting rod will prevent the rotation of the shaft.

It is obvious that a pivotal joint would serve the same purpose as the ball and socket and the pins. Radial vanes 9 in the casing below the disk 4 tend to make the liquid rotate with the casing thereby engendering in the same a centrifugal force. Radial vanes 10 on the upper side of the non-rotatable disk 4 check the circular movement of the liquid with the result that as the speed increases the centrifugal force engenders a suction beneath the disk 4 and a pressure above it which results in a downward motion of the disk with its shaft 5 and rod 6. The hollow space 11 inside the shaft 5 has apertures 12 communicating with a circumferential groove 13 on the outside of the shaft. There is also a passage 14 leading from the space 11 up through the center of the rod 6 to outlets 15 through the side of the rod. As the space 11 is in open communication with the bottom of the disk 4, any air tending to accumulate under the disk, which of course being lighter than liquid would concentrate itself at the center of the disk, is permitted to escape through the space 11 as an air vent and thence up through openings 14 and 15 to the atmosphere. Labyrinthine grooves 16 are provided in the outer surface of the shaft 5. Any liquid passing up the exterior surfaces of the shaft 5 will be checked by the labyrinthine grooves and finally will be forced out through the passage 12 into the center 11 of the shaft.

I claim:

1. In a speed regulator, a rotatable liquid-tight container having a central vertical

110

column rising therefrom and opening there-
into to insure complete immersion of a
governing member, the said container pro-
vided with vanes for producing rotation of
5 the contained liquid, a non-rotating disk in-
side the container with space around it
allowing free communication from one side
of the disk to the other and having vanes
for preventing the rotation of the liquid,
10 the said disk capable of moving axially due
to the difference in pressure above and below
it, the vanes on the container and the vanes
on the disk being on opposite sides of the
disk so as to create such difference of pres-
15 sure, a shaft for the disk movable axially
with respect to the container, and connect-
ing mechanism from said shaft for control-
ling a source of power, the said shaft having
an air vent through it to bleed any air
20 pocketed beneath the disk.

2. A speed regulator as set forth in claim
1, in which the shaft has a journal fit in the
vertical column.

3. A speed regulator as set forth in claim

1, in which the shaft has a journal fit part- 25
way up to said vertical column.

4. A speed regulator as set forth in claim
1, in which the shaft has a journal fit in the
vertical column and side outlets through the
walls of the shaft from the air vent to the 30
journal bearing.

5. A speed regulator as set forth in claim
1, in which the shaft has a journal fit in the
vertical column and side outlets from the
air vent to the journal bearing, and central 35
outlets at the top, the former for discharg-
ing oil from bearing to the air vent and the
latter for venting air.

6. A speed regulator as set forth in claim
1, in which the shaft has a journal fit in the 40
vertical column and a connecting rod from
same to the controller mechanism with a
joint capable of flexure to allow for mis-
alignment of shaft and connecting rod while
45 preventing rotational movement of the con-
nected parts.

CHARLES H. SMOOT.
